UNITED STATES PATENT OFFICE.

YOUNGER HISLE, OF MOUNT STERLING, KENTUCKY.

DESIGN FOR A NUT-LOCK WASHER.

SPECIFICATION forming part of Design No. 32,877, dated June 26, 1900.

Application filed May 29, 1900. Serial No. 18,462. Term of patent 14 years.

To all whom it may concern:

Be it known that I, YOUNGER HISLE, a citizen of the United States, residing at Mount Sterling, in the county of Montgomery and State of Kentucky, have invented a new and original Design for Nut-Lock Washers, of which the following is a specification.

This invention relates to a new and useful design for a nut-lock washer, and the essential feature resides in a plate having a circular contour with segmental wings arranged at an upward or outward angle of inclination toward their free ends and giving the inner portion of the body an approximate triangular appearance.

In the drawings, Figure 1 is a perspective view of a nut-lock washer embodying the features of the design. Fig. 2 is a similar view of the reverse side of the washer. Fig. 3 is an edge elevation of the same.

The numeral 1 designates the body, which is in the form of a plate having a circular contour and provided with tangential cuts or slits 2, which give to the inner body an ap-

proximate triangular appearance and produce segmental wings 3, which extend upwardly from the plane of the outer side of the edge of the plate to their free ends and are thinner than the body of the plate. The said wings have curved outer edges and straight inner edges, and on one side, at the points where they start away from the body 1, are formed with concave recesses 4. A circular opening 5 is formed in the center of the plate, and in triangular arrangement in the said body are smaller openings 6, which have projections 7 therearound on one side of the body.

Having thus described the invention, what is claimed as new is—

The design for a nut-lock washer, herein shown and described.

In testimony that I claim the foregoing as my own I have hereto affixed my signature in the presence of two witnesses.

YOUNGER HISLE.
